HOT-AIR ENGINE.

1,290,756.

Specification of Letters Patent.

Patented Jan. 7, 1919.

Original application filed July 5, 1913, Serial No. 777,432. Divided and this application filed February 14, 1917. Serial No. 148,672.

To all whom it may concern:

Be it known that I, ALEXANDER T. KASLEY, a citizen of the United States, and a resident of Swissvale, in the county of Allegheny and State of Pennsylvania, have made a new and useful Invention in Hot-Air Engines, which is a division of application Serial No. 777,432, filed July 5, 1913, and of which the following is a specification.

10 This invention relates to heat engines and has for an object to produce an improved form of hot air machine in which the expansion and contraction of the inclosed air is employed to actuate a turbo machine instead 15 of a reciprocating piston, as has been customary in the past.

A further object is to produce a hot air machine in which the alternate expansion and contraction of the air is maintained by 20 means of a fire and the reciprocating movements of a slow speed displacer and in which a high speed turbine is employed for transforming the energy of the expanding and contracting air into available power.

25 A further object is to produce a hot air machine in which the energy of the expanding and contracting air is transferred to a liquid.

A further object is to produce a hot air 30 machine in which the energy of the expanding and contracting air is transferred to a liquid which is employed in actuating a power developing or power transmitting device.

35 These and other objects are attained by means of a hot air machine embodying the features herein described and illustrated in the single sheet drawing accompanying and forming a part hereof.

40 The drawing is a diagrammatic sectional view of a hot air machine embodying my invention.

The ordinary forms of hot air engines employ a displacer and a working piston operating in machined cylinders. These cylinders must be relatively large, are clumsy, warp easily, and in the case of the working cylinder must be carefully machined. In my invention I have completely eliminated 45 the working cylinder and derive the power from a turbine instead of the ordinary reciprocating mechanism. The displacer chamber may be made of concrete, brick or any

suitable material. The displacer itself may be cheaply fabricated from standard sheet 55 metal forms. It is shallow and of relatively large area, so that the air may pass through it with little friction. In order to further simplify the apparatus and increase the efficiency I transfer the energy of the air to a 60 body of liquid, water for example, in such a manner that a continuous stream of the liquid is kept circulating throughout a closed system. A turbine of any suitable type, such as an impulse or reaction water 65 turbine, placed in this system transforms the energy of the moving body of liquid into available power. The displacer is actuated by a separate motor and may therefore be operated at a slow speed in order to obtain 70 the highest efficiency.

In the drawing I have diagrammatically illustrated an embodiment of my invention, comprising a displacer chamber 5, which may be formed or built of any suitable material. Inside of the chamber 5, I have shown a displacer 6, consisting of a perforated plate 7, carrying a regenerator 8 on its upper side, and a cooler 9 on its lower side. The regenerator 8 may consist of brick 80 checkerwork, short sections of refractory tubing or any other heat storing material which will allow the free passage of air through it. I have shown the cooler 9 as composed of strips of sheet metal depending 85 from the perforated plate 7, and adapted to dip in the water which fills the lower portion of the displacer chamber 5. A series of vertical open tubes 10 mounted on a bell 10^a are also carried by the displacer 6 and 90 extend up through the roof 11 of the displacer chamber into stationary tubes 12 in which they freely slide. The tubes 12 are closed at their upper ends. The whole displacer 6 is so constructed that the air can 95 freely pass through it. A depending flange 13, which always dips in the water in the lower portion of the displacer chamber 5, acts as a seal between the upper and lower sides of the displacer, preventing the air 100 from passing around the displacer and making an accurate fit with the walls of the chamber 5 unnecessary.

Around the bottom of the displacer chamber 5, on the outside thereof, is shown an annular water chamber 14 crossed by cooling

tubes 15, to which cooling water is delivered by a second annular chamber 16 superimposed on the chamber 14. A conduit 17 is adapted to deliver cooling water to the chamber 16. The lower annular chamber 14 communicates with the lower portion of the displacer chamber 5 through valves 18 which open inward only. The bottom of the displacer chamber 5 is provided with valves 19, which only open outward into a passageway 20. The passageway 20 communicates with a vertical chamber 21, which communicates with a similar chamber 22 by means of the working passages of a turbine 23. A pipe 15 or passageway 24 connects the chamber 22 with the annular chamber 14, thereby forming a closed circulating system, which includes in series the annular chamber 14, the bottom part of the displacer chamber 5, the passageway 20, the chamber 21, the turbine 23, the chamber 22 and the passageway 24.

The displacer 6 is adapted to be raised and lowered in the displacer chamber 5 by the means of a rod 25 extending through the bottom of the chamber 5 and a stuffing box 26 in the wall of the passageway 20. The rod 25 is illustrated as by being actuated by a walking beam 27, which in turn is actuated by a small motor 28 through reduction gearing 29 and a connecting rod 30.

To one side of the displacer chamber 5, I have shown a furnace 31 having a fuel burning grate 32 in open communication with a flue 33 into which the blind-ended tubes 12 extend from the top of the displacer chamber 5. As shown, the flue 33 bends back on itself and terminates in a stack 34. Near the junction of the flue 33 with the stack 34 I have shown an economizer 35 which consists merely of a series of tubes through which air is passed and heated before being delivered to the furnace grate 32 by means of a pipe 36.

The operation of the apparatus illustrated is as follows: A fire being built on the grate 32, the hot gases from the fire rise up through the flue 33 around and between the blind-ended tubes 12, heating them, and on through the economizer 35 to the stack 34. The air heated in the economizer is delivered to the grate 32 and intensifies the heat of the fire, thereby effecting a saving in fuel.

The small motor 28 is started up causing the displacer 6 to periodically rise and fall in the displacer chamber 5. As the displacer 6 rises the air above it is displaced and passes downward through the regenerator and cooler 9 into the lower part of the chamber 5. In its downward path it gives up heat to the regenerator 8 and is further cooled by contact with the depending strips of the cooler 9, which have been cooled by being immersed in the water filling the lower portion of the chamber 5. This cooling of the air causes it to contract, thereby creat-

ing a drop in pressure which draws water from the annular chamber 14 into the lower portion of the chamber 5.

The displacer 6 now moves to the bottom of its stroke, the air is displaced and passes upward through the regenerator 8, recovering heat therefrom, and on up through and around the tubes 10 into the blind-ended tubes 12. Some of this air is, of course, trapped under the bell 10 and is delivered through the tubes 10 to the upper ends of the tubes 12, thereby preventing the latter from becoming overheated. The air is therefore subjected to additional heat and expands so as to raise the pressure in the chamber 5 and consequently forces a part of the water, now in the lower part of the chamber 5, out through the valves 19 into the passageway 20. It is, of course, understood that both the valves 18 and 19 are of a non-return type, such as the common form of pump valves. It is evident that the action just described pumps water from the chamber 22 through the annular chamber 14 and the displacer chamber 5 and into the vertical chamber 21, so that the water level in the latter is higher than that in the chamber 22, provided the air trapped above the water was initially of substantially the same pressure in both of the chambers 21 and 22. Therefore a continuous flow of water through the turbine 23 is maintained by the pumping action of the alternately expanding and contracting air inclosed in the displacer chamber 5. The air inclosed above the water in the chambers 21 and 22 serves as a cushion to prevent water hammer and also serves to accentuate the flow of water through the turbine because of its resilient characteristics.

The displacer illustrated is light in weight and may be cheaply constructed. The cooler 9 is formed so as to offer little resistance when dropped into the water and provides a large radiating surface for rapidly and efficiently cooling the air. The regenerator 8 is preferably made of a refractory material having a low heat conductivity to prevent the loss of heat directly to the cooler. The separate motor 28 allows the relatively bulky displacer to be operated at a slow speed, thereby reducing fluid friction losses in the displacer chamber and allowing ample time for the air to alternately become heated and cooled to the best advantage. The large area and relative shallowness of the displacer allows the velocity of the air in passing through it to be so low that frictional losses are reduced to a minimum.

The cooling tubes 15 in the annular chamber 14 prevent the water in the closed system from becoming heated and to thereby impair the efficiency of the cooler 9.

It is evident that any gas, vapor or liquid may equally well be employed in my invention.

tion to perform the function of the fluid in the closed system, but I preferably employ water because of its cheapness and adaptability.

- 5 In my invention any form of apparatus for expanding and contracting the air may be employed, but I have illustrated the preferred embodiment. The details of the circulating system are also merely illustrative, 10 although of a preferred form when water is employed in the system.

What I claim is:

1. In a heat engine, a displacer chamber, means for allowing fluid to be drawn into 15 the displacer chamber when the air therein contracts, separate means for allowing the discharge of fluid from the displacer chamber when the air therein expands, and a closed system including a turbine for connecting the last mentioned means with the 20 first mentioned means.

2. In a heat engine, a displacer chamber, a displacer, means for reciprocating the displacer in the displacer chamber, means for 25 allowing fluid to be drawn into the displacer chamber when the air therein contracts and a closed system for receiving the fluid expelled from the displacer chamber when the air therein expands and for circulating it through a turbo machine.

3. A heat engine comprising a displacer chamber, a displacer within said chamber for occasioning expansion and contraction of fluid contained within said chamber, a circulatory system communicating with said chamber, and means for transforming energy transmitted to fluid traversing said system into available work, in combination with means whereby the expansion and contraction of fluid within said chamber occasions a circulation of fluid in one direction only through said system.

4. A heat engine comprising a chamber, means for expanding and contracting fluid 45 inclosed within the chamber, a circulatory system communicating with said chamber, an engine included in said system, in combination with means whereby the expansion and contraction of said fluid occasions a circulation in one direction only of the circulating fluid within said system.

5. A heat engine comprising means for expanding and contracting an inclosed fluid, a circulatory system comprising connecting 55 passageways, means for cushioning the flow of fluid through the circulatory system, a turbine, and means for cooling the fluid of the circulatory system, and means for transferring the energy of the expanding and 60 contracting fluid to the fluid in the circulatory system.

6. In a heat engine, a displacer chamber, a displacer therein, a non-return valve responsive to a decrease in pressure within the 65 displacer chamber for admitting fluid to said

chamber, and a separate non-return valve responsive to an increase in pressure within the displacer chamber for discharging fluid from said chamber.

7. A heat engine comprising a displacer chamber, a displacer, means for operating the displacer at a relatively slow speed, and a turbine for transforming the energy of the hot air machine into available power at a relatively high speed. 70

8. In a hot air engine, a displacer chamber, a displacer within said chamber, a combustion chamber, extensions of the displacer chamber exposed to the heat of combustion within the combustion chamber, and opened 80 ended tubes mounted on the displacer and movable into said extensions as the displacer approaches the extensions, said tubes being adapted to establish communication between said chamber and said extension. 85

9. A heat engine comprising a displacer chamber, a displacer within said chamber, a circulatory system communicating with said chamber, and an engine included in said system for transforming energy of the circulating fluid within said system into available work, in combination with means whereby variations of pressure within the displacer chamber occasion flow in one direction only of the circulating fluid within said 90 system. 95

10. A heat engine comprising a displacer chamber, a displacer within said chamber, a closed circulatory system communicating with a discharge port of said chamber and 100 with an inlet port of said chamber, means included within said system and located between said inlet and discharge ports for converting the energy of the circulating fluid within said system into available work, in 105 combination with valves for controlling the delivery of medium through said inlet and discharge ports and for occasioning a flow in one direction only of the circulating fluid within said system. 110

11. A heat engine comprising a displacer chamber, a displacer within said chamber, a closed circulatory system communicating with a discharge port of said chamber and with an inlet port of said chamber, means located within said system and between the inlet and discharge ports of said chamber for converting the energy of the circulating fluid within said system into available work, in combination with a non-return valve responsive to an increase in pressure within said chamber for controlling the delivery of circulating medium through said discharge port, and a non-return valve responsive to a decrease in pressure within said chamber for controlling the delivery of fluid through said 120 inlet port. 115

12. A heat engine comprising a chamber alternately subjected to heat and cold, and provided with an inlet port and a discharge 125 port. 130

port, a closed circulatory system communicating with said ports of said chamber, means included in said system for transforming the available energy of the circulating fluid within said system into available work, in combination with non-return valves between said chamber and said system for controlling the flow of the circulating fluid of said system through said ports and for occasioning a flow of circulating fluid in one direction only through said system.

13. A heat engine comprising a displacer chamber, tubular extensions communicating with said chamber and subjected to heat, a displacer operating within said chamber, hollow open ended tubes mounted on said displacer and each adapted to move into one of said extensions as the displacer moves toward the extensions, and a regenerator mounted on said displacer and intervening between the chamber ends of said tubes and the chamber.

14. A heat engine comprising a displacer chamber, a tubular extension communicating with said chamber and continuously subjected to heat, a displacer operating within said chamber, and a regenerator mounted on said displacer in combination with an open ended tube adapted to move into the extension as the displacer approaches the extension and so located with relation to the displacer that the regenerator intervenes between the chamber end of the tube and the chamber.

15. A heat engine comprising a displacer chamber, extensions communicating therewith and continuously subjected to heat, and a displacer operating within said chamber in combination with open ended tubes which move into the extensions as the displacer approaches the extensions and which are so located relatively to the displacer that substantially all of the fluid within the chamber passes through the extensions on being displaced by the displacer.

16. A heat engine comprising a displacer chamber, a displacer located within said chamber, cooling elements mounted on the displacer and adapted to move into and out of cooling liquid contained within the bottom of the chamber, a circulating system for the cooling liquid communicating with inlet and discharge ports of the chamber, means included in the system for transforming the available energy of the cooling liquid transversing the system into available work, and non-return valves between said chamber and said system for controlling the flow of liquid through the inlet and discharge ports and for thereby occasioning a flow of liquid in one direction only through said system.

In testimony whereof, I have hereunto subscribed my name this 18th day of February, 1917.

ALEXANDER T. KASLEY.

Witnesses:

M. B. GORDON.

It is hereby certified that in Letters Patent No. 1,290,756, granted January 7, 1919, upon the application of Alexander T. Kasley, of Swissvale, Pennsylvania, for an improvement in "Hot-Air Engines," an error appears in the printed specification requiring correction as follows: Page 4, lines 55-56, claim 16, for the word "transversing" read *traversing*; and that the said Letters Patent should be read with this correction therein that the same may conform to the record of the case in the Patent Office.

Signed and sealed this 28th day of January, A. D., 1919.

[SEAL.]

R. F. WHITEHEAD,

Acting Commissioner of Patents.
